ROTARY PUMP OR MOTOR

Theodorus W. Edixhoven, Mobile, Ala.

Application October 21, 1938, Serial No. 236,322

3 Claims. (Cl. 103—127)

This invention pertains to rotary pumps or motors such as disclosed in my British Patents No. 227,342, dated January 15, 1925, and No. 249,940 of April 6, 1926. Pumps of the general type 5 therein shown comprising a cover and a rotating piston working in a conical guide rotatably mounted in a hemispherical casing are well known to the art. Hersey, Patent No. 24,872 dated July 26, 1859, and Rider, Patent No. 10 45,636 dated December 27, 1864, disclose early pumps of this type.

Inherent defects and insufficiencies have long been present in this type of pump due to frictional wear, leakage and other causes and it is 15 the primary object of the present invention to eliminate many of the defects present heretofore in pumps of this type.

It is another object of this invention to produce a pump of this type with a greatly increased output whereby a relatively small pump 20 may do the work which formerly required a much larger installation.

Another object of this invention is to improve the piston and cover of the pump to attain the above mentioned ends.

Another object of the present invention is to improve the structure of the suction and delivery ports of the pump to eliminate objectionable pump noise and to increase the pump output.

Another object of the invention is to make the head free expanding to eliminate misalignment of the pump when used to deliver hot fluids.

Other and further objects of the invention 35 will become apparent as this specification proceeds.

Referring to the drawings:

Fig. 1 is a vertical section of the pump and shaft assembly;

Fig. 2 is a plan of the improved piston and plate illustrating the preferred method of mounting the piston on the plate and the plate to the shaft;

Fig. 3 is a top plan of the improved pump showing the improved form of the suction and delivery ports of the pump;

Fig. 4 is a vertical section view of the hemispherical head; and

Fig. 5 is an end plan of the hemispherical head 50 showing the suction and delivery recesses with the piston and spheroid-conical guide member in position.

Referring to Fig. 1, 1 indicates a suitable base 55 for the pump carrying suction and delivery ports 2 and 3 at its upper extremity. As indicated

in Fig. 3 suction and delivery ports 2 and 3 are suitably streamlined to reduce friction and pump noise. Mounted at one extremity of base 1 is support 4 carrying suitable bearings 5 in which rotates drive shaft 6 of the pump. Suitably 5 mounted at one extremity of shaft 6 is cover 7. Cover 7 may be of any suitable metal and is preferably cylindrically shaped and affixed to shaft 6 in any suitable manner. As illustrated cover 7 is affixed to shaft 6 by suitable keys 8 and extends approximately one-half of the length of said shaft within said base. Base 1 is suitably recessed to receive cover 7 and carries suitable bearing 9 to provide a fluid-tight joint with cover 7 at its periphery. The center portion of cover 15 10 is preferably hemispherically recessed to receive spherical tightening boss 10 of piston 11. Tightening boss 10 is preferably slotted as indicated to receive tongue 12 of shaft 6 and is suitably flattened at one of its axes. It is preferably of a 20 radius equal to approximately the width of piston 11. Piston 11 is set into projections 24 and 25 on cover 7 (see Fig. 2) which carry set screws 22 and 23 registering with spherical boss 10 to 25 provide a fluid-tight adjustable joint between piston 11 and cover 7. Piston 11 is so mounted on cover 7 as to oscillate.

Piston 11 is preferably semicircular in shape and of any suitable material. It is designed to make a fluid-tight joint with the interior wall of 30 head 13. Head 13 is hemispherically recessed and the radius of piston 11 is equal to the radius of this hemispherical recess. Head 13 is preferably hemispherical in shape and is suitably affixed to base 1 as by bolt 14 and projection 26. 35 Base 1 is suitably recessed as indicated to receive head 13.

Clamping screw 16' bears against head 13 whereby it may be adjusted on base 1. Clamping screw 16' is carried by a suitable semicircular 40 bracket, which is preferably pivotally mounted at opposite sides of base 1 about head 13. A vertical section of a portion of this bracket is illustrated in Fig. 1 of the drawings. It will be noted that head 13 is not rigidly affixed to base 45 1. It is preferably affixed to be free expanding to eliminate danger of misalignment should the pump be utilized to deliver hot fluids.

Guide member 15 is suitably rotatably mounted in head 13 as by stud 16. Guide member 15 is 50 preferably spheroid-conical in shape and of any suitable size and material. It is designed to make a fluid-tight connection with the interior wall of head 13 and cover 7. Guide 15 is preferably disposed at about a 45° angle to shaft 55

- 6 and is suitably slotted to receive piston 11. The interior extremity of guide 15 is suitably truncated to provide a fluid-tight joint with spherical tightening boss 10.
- 5 Suitable suction and delivery recesses 17 and 18 are provided in head 13 as indicated in Fig. 5. Suction and delivery recesses 17 and 18 are preferably disposed on opposite sides of guide 15 and are separated from each other by said guide.
- 10 They are preferably spheroid-triangular in shape and register with suction and delivery ducts 2 and 3 in base 1.
- Base 1 carries suitable thrust ring 19 for cover 1 and is provided with suitable packing glands 20 and gland clamp 21 which may be adjusted to prevent seepage of fluid about shaft 6.
- In Fig. 2, 6 represents the drive shaft for the pump to which is suitably affixed cover 7 as by keys 8. Tongue 12 of shaft 6 registers with a suitable slot in spherical tightening boss 10 of piston 11. As illustrated screws 22 and 23 are mounted through suitable projections 24 and 25 of cover 7 into tightening boss 10 to provide a fluid-tight joint between piston 11 and cover 7.
- 20 Tightening boss 10 is shown suitably flattened at one of its axes to form fluid-tight joints with studs 24 and 25 of cover 7. By adjustment of screws 22 and 23 piston 11 may be tightened on cover 7. Piston 11 is preferably so mounted on cover 7 as to oscillate on screws 22 and 23 as an axis.
- In Fig. 3, 1 represents the pump base carrying head 13 and shaft 6. A suitable streamlined configuration of suction port 2 and delivery port 3 is shown. With such a streamlining of the ports little obstruction is opposed to the passage of fluid through the pump with a resulting diminution of noise and wear and with a corresponding increase in output.
- 40 Figs. 4 and 5 show respectively a side section and an end view of head 13. Fig. 4 shows suitable suction or delivery recess 17 and auxiliary recess 27 designed to accommodate cylindrical stud 16 of guide 15.
- 45 In Fig. 5, 13 represents the pump head containing suction recess 17 and delivery recess 18, positioned on opposite sides of guide 15 and separated thereby. These recesses are preferably spheroid-triangular in shape and preferably extend on 50 each side of guide 15 from points near the vertical axis of head 13 to points approximately at its horizontal axis, as shown. Also illustrated is semicircular piston 11 shown in neutral position.
- The improved pump functions as follows:
- 55 On rotation being imparted to shaft 6, from any suitable source of power, cover 7 and piston 11 commence to rotate. This rotation causes opening of suction recess 17 and closes delivery recess 18 from suction recess 17. As the degree 60 of rotation is increased piston 11 slides in guide 15 and takes on not only a rotative movement but also a sweeping movement. As rotation increases the suction area in the hemispherical recess in head 13 enlarges more and more due to 65 the slide of piston 11 in guide 15 until at point of 270° rotation piston 11 clears the delivery recess 18 and the fluid load of the hemispherical chamber is forced out through delivery port 3 in the last 90° of rotation. The cycle is then 70 recommended.
- It must be borne in mind that at all times spheroid-conical guide 15 makes fluid-tight connections with the interior wall of head 13 and with cover 7. Guide 15, moreover, is so recessed 75 at its apex as to form a fluid-tight connection

with tightening boss 10. Furthermore, piston 11, at all times bears in fluid-tight relation against the interior wall of head 13. As all these connections are fluid-tight the full pumping effect is obtained by the ability of piston 11 to slide in 5 guide 15 and the sweep generated by the combined rotation of piston 11 and its slide.

The higher efficiency of the improved pump is due in no small degree to the configuration of tightening boss 10 and screws 22 and 23, which 10 pass through studs 24 and 25 of cover 7. In prior pumps of this type no allowance was made for wear with the result that the connections between piston and cover soon became worn, leakage started and the pump shortly went out of operation. With the present tightening boss, screw and stud arrangement, as soon as wear occurs leakage can be forestalled by a proper adjustment of the tightening screws. Moreover, by utilization of the enlarged tightening boss a 20 greater peripheral sweep is imparted to the fluid in the chamber greatly increasing the power of the pump.

Another feature of the pump lies in the improved cover 7, as illustrated in Figs. 1 and 2. 25 In former pumps of this type the covers comprised comparatively thin metal discs keyed or otherwise affixed at one end of the shaft and rotatable in shallow circular recesses in the base. Great difficulty was experienced with the old type 30 of cover. After comparatively short use it became worn and misaligned due to vibration and shaft whip. This wear and misalignment resulted in leakage past the cover, in freezing of the pump and in general low performance of the 35 installation. Moreover, due to the misalignment, pump fluid leaked into the shaft bearings and caused gumming and clogging of the bearings. Due to the vibration of the cover it was almost impossible to assure a fluid-tight joint between 40 the conical guide and the cover and between the piston and head of the pump. As a result of this leakage the pump became practically unusable.

The present cover eliminates most of these 45 faults. As will be seen in Figs. 1 and 2 the improved cover is cylindrical in form and extends about the shaft approximately one-half of its length in the pump base. The outer extremity of the cover is formed into a cylindrical extended 50 shoulder 7' which bears against bearing 9 applied to the internal wall of the enlarged base recess. The cylindrical body of the cover 7 is extended substantially along shaft 6 as shown and is suitably affixed thereto as by keys 8. The extremity 55 of cover 7 bears against thrust bearing 19 applied about the end of the enlarged base recess.

The improved bearing surface provided by shoulder 7' and by the cylindrical extension of the cover effectively eliminates vibration of the 60 cover. Thus leakage between the cover and base are eliminated and a fluid-tight joint between the various elements is insured. Moreover, with the free expanding and clamping head construction the pressure of the elements against the 65 cover can be regulated and through this regulation the highest pump performance may be procured.

Thus, with the new cover construction vibration, leakage and misalignment of the elements 70 of the pump are eliminated and a performance is procured which was impossible with former pumps of this type.

With this cover it is not necessary to groove the face of the cover along one diameter to pro- 75

vide a recess for the base of the piston. The elimination of this recess and the provision of studs 24 and 25 adjacent the enlarged tightening boss 10 of the piston gives a completely stable 5 combination of the elements and eliminates one of the main prior sources of leakage.

Hot fluids may be delivered by this pump with high efficiency due to the manner in which head 13 is affixed to base 1. In former pumps of this 10 type the head was rigidly affixed to the base at two or more points and the pump was not free expanding. As a result the pump was susceptible to misalignment and freezing due to the unequal expansion of its parts if a hot fluid 15 were passed through it. In the present pump head 13 is expansibly affixed to base 1 by bolt 14, projection 26 and screw 16'. As head 13 and base 1 are thus slidably linked together any expansion occurring within the pump body will be 20 compensated for.

The streamlined configuration of suction and delivery ports 2 and 3 is another factor which contributes to the improved performance of this 25 pump. By constructing these ports as shown in Fig. 3, the fluid entering and leaving the pump follows a smooth curve without striking obstructions. In this way vibration and pump noise are eliminated and output is greatly increased.

The pump is highly efficient. A pump made 30 under these specifications with a cover three inches in diameter, driven at 400 R. P. M. by a 1 H. P. motor will deliver over three and one-half tons of fluid per hour. The same pump has fifteen feet of free suction and is capable of raising 35 the fluid to a height of forty feet when valves are used.

Due to the improved enlarged tightening boss, friction and wear on the piston are greatly decreased due to the added bracing effect imparted 40 to the boss by the sphero-conical guide.

This pump is capable of pumping the more viscous fluids, molasses, honey, etc., and is extremely flexible. Regardless of the viscosity of the fluid delivered its output remains generally 45 constant. For this reason a comparatively small unit can do work which formerly required a large and expensively powered installation.

This invention is susceptible of many adaptations and embodiments. If desired, it can be used 50 as a source of motive power.

Nothing in this specification is intended to limit the scope of the invention; attention being had to the appended claims for this purpose.

What is claimed is:

55 1. In a rotary pump, a base, a shaft rotatably mounted in said base, a cylindrical shouldered, cover mounted about one end of said shaft and rotatable with said shaft in said base, the shouldered portion of said cover bearing in fluid-tight relationship against suitable bearing means in said base, tightening studs carried by said cover, a hemispherical head mounted to be free expanding on said base, a sphero-conical slotted guide rotatably mounted in said head and 60 bearing in fluid-tight relationship against said head and said cover, semi-triangular suction and delivery recesses in said head on opposite sides of said guide and separated thereby, said re-

cesses being disposed in said head substantially from its vertical axis to its horizontal axis, a semi-circular piston mounted to oscillate on said cover bearing in fluid-tight relationship against said head and slidably mounted in the slot in 5 said guide, said piston having a radially inner bearing base comprising a spherical tightening boss flattened at the extremities of one axis running at right angles to said shaft, said flattened portions of said boss bearing against the 10 tightening studs on said cover and screw adjustable therebetween in said cover, and streamlined suction and delivery ports in said base arranged to pass fluid through said pump in a smooth 15 curve and registering with said suction and delivery recesses.

2. In a rotary pump, a base, a shaft rotatably mounted in said base, a cylindrical cover mounted over one end of said shaft extending a substantial distance along said shaft and rotatable in said base, a pair of tightening studs carried by the inner face of said cover, a hemispherical head mounted for free expansion on said base, a sphero-conical slotted guide rotatably mounted in said head at an angle of about 25 45° to said shaft and bearing in fluid-tight relationship against said head and said cover, sphero-triangular suction and discharge recesses in said head on opposite sides of said guide and separated thereby, said suction and discharge 30 recesses extending about said guide substantially from the vertical axis of said head to its horizontal axis, streamlined suction and delivery ports in said base registering with said suction and delivery recesses and designed to pass fluid 35 through said pump without obstruction, a semi-circular piston mounted to oscillate on said cover bearing in fluid-tight relationship against said head and said cover and slidably mounted in the slot in said guide, said piston having a radially 40 inner bearing base comprising a spherical tightening boss fitted between the tightening studs upon the face of said cover and screw-adjustable therebetween, said boss bearing in fluid-tight 45 relationship against said guide.

3. A rotary pump comprising a base, a shaft rotatable in said base, a cylindrical shouldered cover affixed about said shaft for rotation therewith, the shouldered portion thereof bearing against suitable bearing surfaces within said 50 base and rotatable in said base, a substantially hemispherical head adjustably affixed to said base, a hemispherical working chamber within said head, fluid inlet and outlet ports registering with said chamber, a slotted sphero-conical 55 guide rotatably mounted in said head at an angle of about 45° to said shaft separating said fluid inlet and outlet ports, a semicircular piston mounted to oscillate on said cover, bearing in fluid-tight relationship against the wall of said 60 chamber and slidably mounted in the slot in said guide, and a spherical boss adjustably mounted in said cover and of a radius approximately equal to the radial width of said piston and comprising a bearing surface upon which said piston oscillates.

THEODORUS W. EDIXHOVEN.
